SAFETY CLOTHES AND WASH LINE

Guiseppe Grandone, New York, N. Y.

Application May 15, 1939, Serial No. 273,631

8 Claims. (Cl. 211—119.06)

This invention relates to new and useful improvements in a safety clothes or wash line.

The invention has for an object the construction of a safety clothes line which is characterized by a bar pivotally mounted on a bracket intended to be attached on a window frame, and pulleys for a length of the clothes line associated with said bar in a particular manner.

More specifically, the invention contemplates the use of a pair of closely spaced pulleys mounted on the top of the bar in a plane parallel to the plane of pivoting of the bar to guide a length of clothes line outwards from said window in the vertical and horizontal positions of the bar.

Furthermore, the invention proposes a pulley mounted on a bracket which is mounted on the bottom of said bar and arranged in a plane at right angles to the plane of pivoting of said bar to guide said length of clothes line outwards of the window in a horizontal position of the bar and to cause an edge portion of the bracket to bend said length of clothes line in the vertical position of the bar. In the latter condition the clothes line is held against being accidentally moved by the wind blowing the wash which is secured on the line.

Still further the invention proposes a novel arrangement for resiliently mounting the bar and the various pulleys specified to secure a certain tensioning of the clothes line.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a portion of a window frame equipped with a safety clothes line constructed according to this invention.

Fig. 2 is a side elevational view of Fig. 1 showing the bar in its horizontal position and illustrating the window sashes in section.

Fig. 3 is a fragmentary enlarged detailed view of the outer end of Fig. 2.

Fig. 4 is a fragmentary vertical sectional view taken on the line 4—4 of Fig. 2.

Fig. 5 is a horizontal sectional view of a window equipped with a safety clothes line constructed according to a modification of this invention.

Fig. 6 is a horizontal sectional view of the central portion of Fig. 5.

Fig. 7 is a horizontal sectional view of the end portion of Fig. 5.

Fig. 8 is a sectional view taken on the line 8—8 of Fig. 7.

Fig. 9 is a sectional view taken on the line 9—9 of Fig. 5.

The safety clothes line, in accordance with this invention, includes a bracket 10 which is adapted to be attached on a window frame 11 preferably by the use of a number of screws 12. A bar 13 is pivotally mounted intermediate of its ends by a pintle rivet 14 upon the bracket 10. A spacer 15 washer 15 is mounted upon the pintle rivet 14 to hold the bar 13 spaced a short distance from the bracket 10. The bar 13 is of such length and is so arranged to be disposed outside of the window in its vertical position as shown in Fig. 1, and in its horizontal position as shown in Fig. 2, to have one end extended inwards through the window.

A pair of closely spaced pulleys 16 and 17 are mounted on the top of the bar 13 and are disposed in a plane parallel to the plane of pivoting of the bar to guide a length 18 of clothes line outwards of the window in the vertical and in the horizontal positions of the bar 13. The length of clothes line 18 engages over the bottom pulley 17 from the outside inwards. The top pulley 16 then is inoperative. However, when the bar 13 is pivoted to its horizontal position the length of line 18 will engage against the pulley 16 which is now located to the front as clearly shown in Figs. 2 and 3.

The pulleys 16 and 17 are mounted between the arms of a U-shaped bracket 20 which is attached at one of its arms upon one face of the bar 13. Another U-shaped bracket 21 is mounted on the bottom of the bar 13, but this bracket is arranged with its arms at right angles to the face of the bar 13. A pulley 22 is mounted on the bracket 21 in a plane at right angles to the plane of pivoting of the bar 13 to guide said length of clothes line 18 outwards of said window in the horizontal position of the bar. This is clearly shown in Fig. 2. However, in the vertical position of the bar 13, as shown in Fig. 1, the length of clothes line 18 will engage over an edge 21^a of one of the arms of the bracket 21 so as to be bent substantially at right angles. The purpose of this bend is to set up friction to prevent the clothes line from being moved accidentally by the wind blowing wash secured to the line when the bar 13 is in the vertical position.

A means is provided for holding the bar 13 in its horizontal position. This means includes a screw or other holding element 24 mounted upon the bar 13 and cooperative with a threaded boss 55

25 or other complementary element arranged upon the bracket 10. In Fig. 4 the screw 24 is shown engaging the boss 25 for stationarily holding the bar 13. No specific means is required to hold the bar 13 in its vertical position since the weight of the wash upon the line or the tension of the clothes line itself will tend to normally hold the bar in this position.

In the form of the invention illustrated in Figs. 5-9 inclusive, a modification has been shown intended to hold the clothes line resiliently. According to this form of the invention the pintle 14' which pivotally supports the bar 13 is mounted upon a block 28 slidably supported on a casing 29 which is mounted on the bracket 10. Springs 30 are mounted within the casings 29 and act against opposite sides of the block 28 to resiliently support the block. An adjustment screw 31 is threadedly engaged through one end of the casing 29 and engages one end of one of the springs 30 by which the springs may be compressed or released to adjust the floating resiliency of the block 28. The pintle 14' is provided with a wing screw 14" adapted to clamp the bar 13 in its horizontal or its vertical position and permitting removal of the bar 13 when desired.

The bracket 21 is also mounted upon a block 28 slidably mounted in a casing 29 which is mounted on one end of the bar 13. Springs 30 are disposed within the casing and act against opposite sides of the block 29 for resiliently holding the block. An adjustment screw 31 threadedly engages through one end of the casing 29 and abuts one of the springs 30 to permit tensioning of the springs to control the resilient floating condition of the block 28.

The bracket 20 is supported by a pair of pins 33 engaging through a slot 34 formed in the bar 13 and mounted upon a block 28 slidably mounted in the casing 29 secured to the rear face of the bar 13. Springs 30 are arranged within this casing 29 and act against opposite sides of the block 28 for resiliently supporting the block. An adjustment screw 31 threadedly engages through one end of the casing 29 and abuts one end of one of the springs by which the compression of the springs may be controlled.

The operation of the device is as follows:

In Fig. 1 the safety clothes line is shown in its inoperative position. In this position the clothes line 18 will be held against being moved because of the right angle bend at the point where the clothes line 18 engages over the bracket 21 and under the pulley 22. However, the bracket 13 may be swung around to a horizontal position as shown in Fig. 2 and then the clothes line 18 is free to be moved. Furthermore, one end portion thereof is then within the window.

In the form of the invention shown in Figs. 5 to 9 the various springs 30 will provide sufficient tension to support the clothes line in a taut position. This facilitates hanging of clothes upon the line and moving the line.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Patent is:

75 1. A safety clothes line, comprising a bracket

for attachment on a window frame, a bar pivotally mounted on said bracket to be disposed outside of said window in its vertical position and in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line in a vertical position of the bar.

2. A safety clothes line, comprising a bracket for attachment on a window frame, a bar pivotally mounted on said bracket to be disposed outside of said window in its vertical position and in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line in a vertical position of the bar, said pair of pulleys being mounted in a U-shaped bracket having its arms disposed upwards.

3. A safety clothes line, comprising a bracket for attachment on a window frame, a bar pivotally mounted on said bracket to be disposed outside of said window in its vertical position and in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line in a vertical position of the bar, said pair of pulleys being mounted in a U-shaped bracket having its arms disposed upwards, and being attached by one of its arms to said bar.

4. A safety clothes line, comprising a bracket for attachment on a window frame, a bar pivotally mounted on said bracket to be disposed outside of said window in its vertical position and in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line

75

in a vertical position of the bar, said bottom bracket being of U-shape and having its arms at right angles to said bar.

5. A safety clothes lines, comprising a bracket for attachment on a window frame, a bar pivotally mounted on said bracket to be disposed outside of said window in its vertical position and in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line in a vertical position of the bar, said bar being also resiliently mounted relative to said bracket.

6. A safety clothes line, comprising a bracket for attachment on a window frame, a bar pivotally mounted on said bracket to be disposed outside of said window in its vertical position and in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line in a vertical position of the bar, said bar being also resiliently mounted relative to said bracket, and said pair of pulleys being resiliently mounted with respect to said bar.

7. A safety clothes line, comprising a bracket for attachment on a window frame, a bar pivotally mounted on said bracket to be disposed outside of said window in its vertical position and

in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line in a vertical position of the bar, said bar being also resiliently mounted relative to said bracket, and said pair of pulleys being resiliently mounted with respect to said bar, and said latter mentioned bracket being resiliently mounted with respect to said bar.

8. A safety clothes line, comprising a bracket for attachment on a window frame, a bar pivotally mounted on said bracket to be disposed outside of said window in its vertical position and in its horizontal positions to have its bottom end extended through said window, a pair of closely spaced pulleys mounted in the top of said bar in a plane parallel to the plane of pivoting of said bar to guide a length of clothes line outwards of said window in the vertical and horizontal positions of said bar, a bracket mounted on the bottom of said bar, a pulley mounted on said bracket in a plane at right angles to the plane of pivoting of said bar to guide said length of clothes line outwards of said window in the horizontal position of said bar, and said bracket having an edge portion to bend said length of said clothes line in a vertical position of the bar, said bar being also resiliently mounted relative to said bracket, and said pair of pulleys being resiliently mounted with respect to said bar, and said latter mentioned bracket being resiliently mounted with respect to said bar, said resilient mountings including casings, blocks slidably mounted in said casings, springs within the casings engaging opposite sides of the blocks, and means for controlling the tensions of said springs.

GUIDEPIPE GRANDONE.
